ATTY

UNITED STATES PATENT OFFICE.

FREDERICK H. BULTMAN, OF CLEVELAND, OHIO.

BOTTLE.

SPECIFICATION forming part of Letters Patent No. 573,760, dated December 22, 1896.

Application filed February 6, 1896. Serial No. 578,253. (No model.)

To all whom it may concern:

Be it known that I, FREDERICK H. BULTMAN, a citizen of the United States, residing at Cleveland, in the county of Cuyahoga and State of Ohio, have invented certain new and useful Improvements in Bottles; and I do hereby declare that the following is a full, clear, and exact description of the invention, which will enable others skilled in the art to which it appertains to make and use the same.

My invention relates to improvements in bottles constructed to prevent fraudulent refilling; and the invention consists in a bottle having a breakable neck and a rigid sealing cap, constructed, combined, and arranged substantially as shown and described, and particularly pointed out in the claims.

In the accompanying drawings, Figure 1 is a vertical central sectional elevation of a bottle containing my invention and showing the parts in sealed condition as appears when the bottle is filled and ready for the market. Fig. 2 is a vertical sectional elevation of the neck of the bottle alone and of the cap adapted to fit over the same, but separate therefrom, and shown as it appears before it is applied to the bottle. Fig. 3 is a sectional detail of the cap alone, crimped or contracted about its lower portion, as occurs when it is fitted to the neck of the bottle, as hereinafter described. Fig. 4 is a plan view of the cap on which is a fanciful trade-name, but intended to always bear the trade-name of the contents of the bottle, whatever it may be.

A represents the bottle, which may be of any desired pattern or kind, and B is the neck thereof. The neck in all cases should be made heavy or strong enough to withstand a forcible introduction of the cork by the quick action of machinery, thereby preventing possible injury to the neck at the point of its annular reduction 2. This reduction is made, as here shown, by two opposite annular grooves, channels, or depressions some distance below the mouth of the neck and of course below the upper end of the cork C, the relations being, say, substantially as shown in the drawings or thereabout, the exact relation not being material, provided that the cap come down well over the cork, whereby when the cap and the inclosed portion of the neck are detached the cork will be exposed.

I might of course force the cork still lower in the neck and depend on a corkscrew to withdraw it, but this is not preferable or desirable. The better way is to have the cork flush with the mouth of the bottle and the cap fitting snugly upon the same and over the neck of the bottle in the manner shown.

The reduced part 2 of the neck should be of such strength or durability as to withstand ordinary wear and tear in shipping and handling and yet be small or fragile enough to be easily severed when opening is required. I make the reduction by means of both inner and outer grooves or channels opposite one another, so as to leave an inner rounded surface for the mouth of the bottle after the severing has been effected, thereby leaving the mouth in point of construction and convenience for inserting the cork very much like the ordinary bottle of commerce. This makes the bottle convenient for corking by the person who has purchased the package in its original sealed condition, and fraud is prevented, because when the seal has been broken and is missing the purchaser knows at once that the bottle is not in its original condition. Furthermore, the trade-name or brand also is gone, because this name is on the cap and the cap is made to apply said name thereto.

Now in order to make a perfect seal and one which cannot be broken without also breaking the bottle I use a glass or equivalent style of cap D. This cap is adapted to fit snugly over the plain cylindrical neck B, there being no bead or flange about the mouth of the bottle, as usually occurs, and the neck being made strong enough to withstand the cork without other reinforcement. Glass is altogether preferable for this cap, but any other material that can be used in the same way may be substituted. As here shown, Fig. 2, the cork C having been inserted, the cap is placed in position over the neck and cork, and the cap is then heated round about outside the annular groove in the neck within until it can be molded or depressed to conform to said groove, as seen in Figs. 1 and 3, and this being done the sealing has been effected and the bottle is ready for the market.

If found practicable or desirable, the cap may be first heated to a moldable condition and then placed on the neck and shaped there-

to while it remains heated, and thereby lock it in position.

Hereinbefore I have referred to frangible material, like glass, as best adapted to serve all the purposes of the cap of the bottle, and this is correct; but I may also use a metallic or like cap which has its edge engaged in or upon the annular channel shown in Figs. 1 and 2, or over the annular bead, as shown in Fig. 5. Thus in Fig. 5 I show a modification of the invention in which the reducing-channel is on the inside of the neck and an annular rib or bead 4 is formed on the neck E. This bead has the breaking-point about its bottom at 5, where the glass is lightest, and a metallic or equivalent cap G is engaged over said bead at its bottom. This cap is formed originally as seen in Fig. 6, and after being slipped over the mouth of the bottle is bent inward about its lower edge in engagement with the said bead, as shown. A glass or other cap would be made the same way if to be used with a bead. In any case the material used for the cap must be so rigid and firm that it cannot be removed from the neck of the bottle and the bottle be opened without breaking off the top of the neck engaged by said cap.

What I claim as new, and desire to secure by Letters Patent, is—

1. The bottle having a neck with a shoul-dered breaking-groove about the same and a smooth even exterior above said groove, in combination with a rigid cap directly in contact with the surface of said neck above said groove and bent inward at its lower portion to engage over the shoulder of the said groove,

whereby the bottle is so closed that it cannot be opened without breaking the neck, sub-stantially as described.

2. A bottle provided with a single annular shoulder about its neck and a reduced portion coincident with said shoulder on which the neck is broken off to open the bottle, the exterior of the neck being plain and smooth above said shoulder, in combination with a cap of rigid material pressed into immediate contact with the surface of said neck above and about said shoulder and having its lower edge bent inward to lock on said shoulder, substan-tially as described.

3. The bottle, substantially as described, having a neck with an annular shouldered groove forming a breaking-line when the bot-tle is opened and said neck having a plain in-terior and exterior surface above said groove, in combination with a cap of rigid material fitting closely upon the top edge and sides of said neck above the said breaking-line and having its lower edge bent inward and en-gaged beneath the shoulder of said groove, the said cap being such that the bottle cannot be opened without breaking the neck, and a cork in said neck extending above said break-ing-line and bearing directly against said cap, substantially as described.

Witness my hand to the foregoing specifi-cation on this 1st day of February, 1896.

FREDERICK H. BULTMAN.
